UNITED STATES PATENT OFFICE.

CLARENCE S. WOODMAN, OF WICHITA, KANSAS.

CAR-COUPING.

SPECIFICATION forming part of Letters Patent No. 311,798, dated February 3, 1885.

Application filed September 10, 1884. (No model.)

To all whom it may concern:

Be it known that I, CLARENCE S. WOODMAN, of Wichita, in the county of Sedgwick and State of Kansas, have invented a new and 5 useful Improvement in Car-Couplings; and I do hereby declare that the following is a full, clear, and exact description of the same.

My invention relates to car-couplers of that class where the link is elevated to meet the 10 mouth of the draw-head of the car to which the first is to be coupled. Heretofore various devices have been constructed for this purpose, all more or less complicated, for which reason alone they were objectionable. The 15 major part of those particularly designed for freight-cars and for use in connection with the ordinary link and pin have been constructed of levers bent in a variety of shapes, with the ends thereof projecting from the car- 20 body to or beyond the vertical plane of the end of the draw-head. Such devices in a sudden collision of cars are liable to be bent out of shape and position, and in such case will prove inoperative to lift the link.

25 It is the object of my invention to overcome the existing difficulties incident to this class of couplers, and to attain this object I provide a flexible connection secured to one side of the coupler and connected to a lever on the other 30 side, whereby the link is operated by a positive action, and by reason of the flexibility of the lifting medium no displacement can possibly occur.

My invention consists in the improved construction and arrangement of the parts of the 35 coupler whereby I secure the desired effect.

It also consists in certain details of construction, all as hereinafter described, and particularly pointed out in the claims.

40 In the drawings accompanying this application I have illustrated my coupler as applied to a freight-car of ordinary construction.

Figure 1 represents an elevation of a car with my coupler attached. Fig. 2 is a side 45 elevation of the same; Fig. 3, a perspective view.

In these drawings the draw-head A is in most respects like other draw-heads as ordinarily used. The single exception lies in 50 forming the upper half of the draw-head with

a projecting portion overhanging the lower half. The purpose of this is that when two cars approach each other these projecting portions will meet and act as bumpers to withstand the shock. If, when the cars come together, they are to be coupled, the operator will have the link in line with the mouth of the draw-head, and will cause the pin of the next car to drop at the proper instant; but if it is not desired to couple the cars the link 55 is not moved, and at the angle at which it hangs from the draw-head in which it is secured it will pass below the draw-head of the approaching car, and by reason of the cut-away portion or irregular face of the draw-head will be safe from injury by the shock of the meeting cars. The pins to secure the links in place may be spring-pins, as shown, or of ordinary construction. Any suitable form of pin may be used for the purpose, and a handle-lever connected to the pin by a chain may 60 extend to the side of the car, as shown, within reach of the operator.

My improved means for elevating the link and to guide it to the mouth of the draw-head 75 of the opposite car consists of a chain, B, which is secured to the draw-head upon one side by an eyebolt, a projection from the draw-head with an opening therein, or from the projecting end of a plate or strip attached to the draw-head. This chain passes down under the projecting part of the draw-head and up the other side, where it passes through a guide-opening 80 composed of an eyebolt, a projection from the draw-head, or through an opening in the projecting end of a plate, as shown. The end— 85 which is of a length sufficient for the purpose intended—is secured to the end of a lever, C, secured to the end of the car, the said lever projecting beyond the side of the car, and having a suitable handle by which the operator may grasp it. The lever is preferably guided 90 in its up and down movement by an elongated staple, a, as shown.

In the operation of the device, when it is 95 desired to couple two cars, the operator simply depresses the handle of lever C, which elevates the inner end, thus drawing on the chain and elevating the end of the link to the line of the opposite draw-head. The pin in that 100

draw-head has meanwhile been lifted, and as the cars come together the link is guided to the mouth of the opposite draw-head, and the moment it enters the pin is allowed to fall, and 5 the cars are then coupled.

It will be observed that various forms of levers may be provided for the purpose of drawing on the chain; and I do not of course limit myself in this particular. The chain 10 may also be secured to the draw-head in any suitable manner; and it is not essential that the guide upon the opposite side of the draw-head be attached thereto, as it may project from the end of the car.

15 It will be understood that the construction described is applied preferably to each end of the car alike. It is possible, however, to couple a car with my invention to an ordinary link-and-pin car.

20 Having thus described my invention, what I claim as new is—

1. In a car-coupling, and in combination, a draw-head, a link and pin adapted thereto, a chain secured to one side of the said draw-head and passing under the link and through a guide on the opposite side of said draw-head, and a hand-lever connected to the end of said chain, all substantially as described.

2. In a car-coupling, and in combination, a draw-head, a link and pin adapted thereto, a 30 chain secured to one side of the said draw-head and passing under the link and through a guide on the opposite side of said draw-head, and a hand-lever connected to the end of said chain, all substantially as described.

3. In a car-coupler, the draw-head formed with the upper half overhanging the lower portion, as described, in combination with the link and pin and flexible means for elevating the link, substantially as described.

40 In testimony whereof I have signed my name to this specification in the presence of two subscribing witnesses.

CLARENCE S. WOODMAN.
